UNITED STATES PATENT OFFICE.

DAVID E. HUNTER, OF MUSKEGON, MICHIGAN, ASSIGNOR TO THE SHAW-WALKER COMPANY, OF MUSKEGON, MICHIGAN, A CORPORATION OF MICHIGAN.

CARD-INDEX SYSTEM.

Application filed April 11, 1927. Serial No. 182,741.

This invention relates to improvements in card index systems and more particularly to systems for filing of reference and like cards and embodying the general characteristics disclosed in Letters Patent No. 1,539,411 granted to E. W. Davis on May 26, 1925, namely, the use and provision of interconnected card-holding members which, when expanded vertically with the drawing of the rearmost card-holding member or guide card from the drawer or cabinet, exposes the top edges of all of the cards to view simultaneously, thus enabling the operator to select the desired card by its title heading without thumbing through the entire group of cards as is the ordinary practice.

While such a system is of unquestionable merit, experience and usage has revealed certain faults which have tended to lessen its practicability for all purposes and ability to withstand hard usage and careless manipulation by operators.

To enumerate some of the objections to the so-called "visible" systems of card indexing of the above mentioned type, which the present invention seeks to correct, there may be mentioned: The inability of the card-holding members to remain extended without being held by the operator, the failure of the cards to remain seated in the card-holding members when the same are collapsed, thus necessitating a final tapping of the cards into place, the absence of means for limiting the withdrawal of the card-holding members with the attendant possibility of tearing and otherwise disorganizing the system, and finally, the disruption of the card-holding members in an attempt to insert or stuff too many cards into one member.

The elimination of these and other defects in the ordinary systems is, therefore, the object of the present invention, a preferred embodiment being disclosed in the accompanying drawings in which:

Figure 1 is a view in front elevation of an ordinary card-filing drawer showing one of the units expanded.

Figure 2 is a view in vertical section lengthwise of a drawer showing several card-holding units in normal position.

Figure 3 is a similar view showing one of the units in expanded position.

Figure 4 is a view in front elevation of one of the units removed from the container. 55

Figure 5 is a view in rear elevation of the unit removed from the container.

Figure 6 is a view in front elevation of one of the card-holding members removed.

Figure 7 is a view in rear elevation of the front portion of one of the card-holding members connected with a similar member in front, the two portions of the figure showing the two members in their normal and extended positions. 65

Figure 8 is a perspective view of the two members shown in Figure 7, but partially unfolded to show the interlocking connection;

Figure 9 is a view in rear elevation of a plurality of card-holding members in extended position and with the guide card removed; and

Figure 10 is a view in section taken on line 10-10 of Figure 5. 75

As a container for the cards and card-holding units, a drawer 1 of the type which slides into and out of a filing cabinet is used as illustrated, although a cabinet or other suitable holder may be used. A series of 80 cards 2 are arranged in any desired order from front to rear of the container, with alphabetical titles or reference headings 2^a along their upper marginal portions. Extending lengthwise and centrally of the bottom wall of the drawer 1 is the usual slot 1^a. A removable guide rod 3 extends along said slot from front to rear of said drawer and just below the surface of the bottom thereof. The rod has the usual knob 3^a at its forward 90 end having threaded connection with the front of the drawer. 85

Referring now to the card-holding devices, the same consists of a number of units or sections placed one behind the other 95 throughout the length of the drawer, each section or unit being made up of an anchor card 4 at the front, having a tab 4^a at its lower edge through which the rod 3 passes, a series of interconnected and telescopic individual card-holding members or pockets 5, arranged one behind the other beyond the anchor card, and finally a guide card 6 of relatively stiff card board, and identified by the guide tab 6^a along its upper edge. By 100 preference, the number of card-holding mem-

bers 5 in a series is limited in number to say, ten or twelve, each member forming an upwardly opening pocket in which a single card is held, these pockets being closed at their lower edges. There are as many units in the drawer as its length will permit. It may be desirable, and particularly when the drawer is of considerable length, to divide it lengthwise into several compartments by inserting partition walls 7 crosswise of the drawer at intervals, thereby separating the units into groups so as to prevent crowding and excessive compression of the units.

Each individual card-holding member 5 is made from a sheet of tough paper or light cardboard cut into a blank and folded in the following manner (Figures 6 and 8): These blanks are generally rectangular in shape and are divided into two main portions 8 and 9 by a transverse bottom fold line 10. The portion 8 is slightly wider and forms the front wall of the card-holding member when the portions are folded together and assembled with the other members. Similarly the portion 9 forms the back or rear wall of the pocket, its height, measured from the fold line 10 to its opposite edge, being slightly less than the width of the card to be held thereby, so that the top margin of the card will project above the pocket. Along the opposite side edges of the rear portion 9 are flaps 9^a, 9^a, which are folded rearwardly or away from the front wall portion 8 along vertical fold lines 9^b. These flaps terminate short of the bottom fold line 10 by a distance of about $\frac{1}{4}$ to $\frac{1}{5}$ of an inch, this representing the distance of relative sliding or shuffling movement between each member and its adjacent members. The spaces between the lower edges of the flaps 9^a and the fold line 10 are a part of two cut-out portions on opposite sides of the blank, and which continue beyond said fold line into the body of the front wall 8. Thus the edges of these cut-out portions extend from the lower edges of the flaps 9^a to the bottom fold line 10 and thence taper slightly inward as they cut into the front wall 8, for a distance of about $\frac{3}{4}$ of an inch, and then turn abruptly toward each other, almost at right angles and finally form deep edgewise-opening notches 11, 11 about $\frac{1}{4}$ of an inch wide at their inner ends and diverging gradually toward the side or vertical edges of the wall portion 8 (Figure 6). Along the top edge of the front wall portion 8 is a longitudinal flap 12 of about an inch in width folded forwardly and downwardly away from the rear wall portion 9, along a fold line 12^a parallel with the bottom fold line 10. The distance between the fold lines 12^a and 10 is equal to the width of the rear wall portion 9, so that both front and rear walls are of the same height when folded in position for assembly.

Figure 8 shows the manner in which the several card-holding members 5 are connected together, namely, by interlocking the rear wall portion of one member with the front wall portion of the member just behind, and so on through the depth of the unit. This connection is a two-fold one, as follows: First, the top flap 12 of the front wall 8 is simply folded or hooked over the top edge of rear wall 9 of the member in front, while the vertical flaps 9^a, 9^a of said rear wall are interlocked with the notches 11, 11 near the bottom of the front wall so that the corners or shoulders below the notches are disposed between the rear wall and its flaps, as clearly shown in Figure 7.

Now considering that the member in the rear is shifted vertically and the member in front is held stationary (Figure 7 on the right) it will be seen that a limited relative movement is permitted, by the spacing of the lower edges of the flaps 9^a, 9^a of the stationary member from the bottom fold line 10 of the member being moved, by a distance of about $\frac{1}{4}$ of an inch. Hence the rear member can be shifted until stopped by the bottom edges of the flaps 9^a, 9^a striking the bottom fold 10 in the front member. This movement therefore permits the top edge of the rear member to be displaced or offset by the same distance above the relatively stationary member, so that the card held in the shifted member will be elevated above the card held in the member immediately in front, and so on, throughout the entire unit.

It follows therefore that each member from front to rear will be elevated or offset above the member immediately in front by the same distance and therefore the cards held in each individual member will be similarly offset with their top marginal portions exposed to view from the front as shown in Figure 1.

Likewise in closing or collapsing the two members used to illustrate the method of interconnection, (Figures 6, 7 and 8) the member that has been elevated may be moved downwardly into its initial position but only a limited distance since the top edge of the wall 9 will strike the fold 12^a formed by the flap 12 and thus bring it to rest exactly behind the stationary member. This same limitation of downward shifting movement between members applies to all members in a unit, so that even though the bottom wall 9 of the drawer were not present to limit the downward movement, they would still be restrained from becoming disconnected, providing they were at the same time pressed together sufficiently to prevent the flaps from drawing out of interlocking connection. Thus it will be seen that the present construction provides for limiting the relative movement between each holding member in a downward as well as an upward direction.

Having thus far considered a plurality of card-holding members connected together in a series, the completion of the unit requires the attachment of the anchor card 4 at the front and the guide card 6 at the rear.

As a convenient method of inserting the anchor card in place at the front of the unit, it is preferably made in duplication of the rear wall portion 9 of a card-holding member, that is, with flaps 4^b, 4^b along its side edges and terminating short of the bottom edge at a distance of about $\frac{1}{4}$ of an inch as in the card-holding members (Figure 4). In this way the anchor card interlocks with the notches 11, 11 of the front wall of the first card-holding member, whereby the latter can be elevated above the anchor card which is held stationary by the rod 3 passing through the tab 4^a at its bottom. The anchor card, however, is of only one thickness of card board, and therefore to secure the front flap 12 of the first card holding member, two spaced slits 4^c, 4^c are cut in its top edge to form a tongue 4^d which grips the central portion of said flap as shown in Figure 4.

The guide card 6 may be attached at the rear of the unit in any suitable manner, the simplest perhaps being to paste the rear wall of the last card-holding member flat against the front face of the guide card.

To complete the unit for assembly in a drawer, an anchor blade or spring leaf 13 is provided which coacts with the guide card 6 to hold it in any position of elevation and also to exert a certain amount of pressure against the back of the guide card to hold the unit under compression. This blade 13 is a thin strip of steel of a length substantially equal to the width of the guide card. The lower end of the blade extends below the bottom of the card-holding members and into the slot 1^a in the bottom of the drawer. Near the lower end of the blade is a hole 13^a through which the rod 3 passes and beyond the hole, the end portion of the blade is bent into the form of a U-shaped clip 14 extending forwardly beneath the rod 3 and then upwardly, terminating just in front of the anchor card 4 in an upstanding finger 14^a having a semi-circular slot 14^b seating against the rod 3.

It is preferred to form the clip 14 separately from the blade 13, and attach it to the lower end of the blade adjacent the hole 13^a, although both can be made in one piece if desired by bending the lower end of the blade.

The length of the clip 14 from front to rear is such that it is just equal to the thickness of the unit when filled to its normal capacity. Thus when the unit is inserted between other units the U-shaped clip determines the space to be occupied by its associated unit and prevents over-crowding and

undue compression of the units to such an extent as to interfere with their manipulation.

As already stated the blade 13 extends vertically behind the guide card 6 which has frictional sliding engagement therewith through the medium of a tension clip 15, which straddles a slot 6^b in the bottom edge of the guide card. The tension clip is made from a strip of light metal arranged transversely of the blade with free end portions riveted to the card on either side of the plate. Near the top and bottom edges of the strip are narrow parallel slots 15^a, 15^a through which the blade is threaded, the tension between the blade and the clip creating a frictional sliding contact between the two, sufficient to hold the guide card in any position along the blade. In order to limit the relative sliding movement of the guide card along the blade 13, the latter is provided with projections 16, 16 punched out near its upper and lower ends. Thus in withdrawing the guide card in order to expose the cards 2 in the particular unit being manipulated, the frictional contact between the clip 14 and the blade holds the unit in extended position, either to its fullest extent or to any intermediate position, independently of the remaining units or of the pressure exerted to compress the unit, thus leaving both hands of the operator free to withdraw the desired card or cards or to make notations therefrom. It should be noted also that the stop projection 16 at the upper end of the blade is so located that the guide card cannot be withdrawn to a greater height than the full expansion of the card-holding members, thus preventing the members from being extended too far and the same torn or disconnected. Similarly to return the cards to their closed position in the drawer it is only necessary to push the guide card downwardly to its seat, whereupon the remaining card-holding members telescope or collapse, carrying the cards with them.

Among the improved features heretofore mentioned as existent in the system herein described is that of successfully overcoming the tendency of cards to become unseated in card-holding members while the same are being closed, and thus creating the necessity of tapping them down into place. This unseating of the cards is due to the shuffling action which takes place between the cards and the walls of the card holding members as they are being shifted, but is only effective during the downward shuffling movement inasmuch as they are positively elevated by engagement with the bottom folds of the card-holding members. Moreover, the tendency to unseat is attributable to the relative degree of friction between the two faces of the card and the surfaces of the card-holding

- members in contact therewith, so that the excess of friction exerted on the rear face of the card may be just enough to unseat and prevent it from following its card-holding member to the bottom. In the form of card-holding member herein disclosed, the card has contact with its holding member on both faces and throughout the greater part of its area on both sides, in fact, it only has contact with an adjacent member throughout the area of the flap 12 of the member behind, which is relatively small. As a result therefore the balance of friction exerted on the card is in favor of its remaining seated in its holding member rather than being unseated.
- It is with thin cards or light sheets of paper that is unseating tendency is particularly pronounced as they have not sufficient weight to overcome the friction, nor have they the stiffness to respond to tapping. Hence in some instances it may be necessary to increase the frictional resistance to unseating by impressing a plurality of projections throughout an area of the rear wall portion 9 of each card-holding member near its lower central portion as at 17, Figures 8 and 9, these projections being on the inner face of the card and having the tendency of thickening the wall just enough to create a gripping action of the card-holding member on the card and prevent it from being dislodged from its seat during the closing of the unit.
- In constructing the unit various details may be modified without departing from the spirit of the invention, both in materials used and arrangement of parts, and for this reason I do not wish to limit the invention to the precise disclosure except in so far as included in the appended claims.

I claim as my invention:

1. In a card index system, the combination with a container of a plurality of individual card-holding members having interlocking sliding connection adapted to permit the relative displacement of said members and means coacting with one of said card-holding members for holding the same in displaced position.
2. In a card index system, the combination of a plurality of card-holding members placed one behind the other and having interlocking sliding connection whereby each member may be shifted a predetermined distance beyond its adjacent members, and means coacting with one of said members for limiting the shifting movement of said members and holding the same in shifted position.
3. In a card index system, the combination with a container of a plurality of card-holding members having interlocking sliding connection permitting a limited relative displacement thereof, means for anchoring the

one of the end members in said container and means coacting with the other end member for holding the same in displaced position.

4. In a card index system, the combination with a container of a plurality of card-holding members normally placed one behind the other and in said container and having interlocking sliding connection with each other, whereby each successive member from front to rear may be offset at a predetermined distance above its adjacent members in the vertical withdrawal of the rearmost member, and means coacting with said rearmost member for limiting the vertical movement thereof and frictionally holding the same in withdrawn position.

5. In a card index system, the combination with a container of a plurality of interconnected card-holding members normally placed in line one behind the other and adapted to be displaced vertically with each successive member offset above its adjacent member, and a member held against vertical displacement relative to said container and having sliding engagement with one of said card-holding members for frictionally retaining the same in displaced position.

6. In a card index system, the combination with a container of a plurality of interconnected card-holding members normally placed one behind the other and resting on the bottom of said container, said members having interlocking sliding connection with each other whereby each member is capable of limited reciprocation relative to an adjacent member, in the vertical upward and downward movement of the rearmost member, and a member held against vertical displacement from said container and having frictional sliding engagement with said rearmost member, said member acting to limit the movement thereof and to hold the same in displaced position.

7. In a card index system, the combination of a plurality of interconnected card-holding members placed in line one behind the other and normally adapted to rest at their bottom edges on a supporting surface, a guide card secured to the rearmost card-holding member, a vertical strip of resilient material fixed at its lower end, said guide card being adapted to have frictional sliding engagement with said strip.

8. In a card index system, the combination of a container, a plurality of interconnected card-holding members placed in line one behind the other in said container and normally adapted to rest at their bottom edges on a supporting surface, a guide card secured to the rearmost card-holding member, a resilient strip fixed at its lower end to said container against vertical displacement and extending upright adjacent said guide card, a member mounted on said guide card

and having frictional sliding engagement on said strip and coacting means on said last-mentioned member and said strip for limiting the vertical displacement of said 5 guide card.

9. In a card index system, the combination with a container of a plurality of card-holding members normally placed one behind the other and resting on their bottom 10 edges in said container, said members having interlocking sliding connection whereby said members are uniformly offset one above the other from front to rear in the vertical displacement of the rearmost member, 15 and a blade secured to the bottom of said container and extending vertically behind the rearmost member, a tension clip fixed to said rearmost member and having frictional sliding engagement with said blade. 20 10. In an index system, the combination with a plurality of cards, of a plurality of individual card-holding members of fibrous material placed one behind the other and normally supported in upright position, 25 each of said members being adapted to have limited sliding movement in a vertical direction relative to the member in front thereof whereby said members are successively offset above each other from front 30 to rear in the vertical withdrawal of the rearmost member, and means for causing a frictional contact between each of said members and the card held thereby.

11. In a card index system, the combination of a container, a series of cards, a plurality of individual card-holding members placed one behind the other and normally supported in upright position in said container, each of said members consisting of a 35 sheet of fibrous material folded double to form an upwardly opening pocket adapted to receive a card with its top marginal portion projecting from the pocket and being adapted to have interlocking sliding connection with its adjacent members whereby in the vertical withdrawal of the rearmost member the top margins of the cards are successively offset above each other from front to rear, and means for increasing the 40 frictional contact between a card-holding member and its card to hold the latter in its pocket in the relative movement of said members into normal position.

12. In an index system, the combination 45 of a container, a series of expandable card-holding units mounted in said container, each of said units comprising a plurality of individual card-holding members of fibrous material placed one behind the other and 50 normally supported in upright position in said container, each of said members being adapted to have limited sliding movement in a vertical direction relative to the member in front thereof, means for anchoring 55 the foremost member of each unit in said

container, means for frictionally holding the rearmost member in displaced position, and means for regulating the longitudinal space occupied by each unit in said container.

13. In a card index system the combination of a container, a plurality of card-holding members placed in line one behind the other and normally adapted to rest at their bottom edges in said container, said members 70 consisting of sheets of fibrous material each folded double to form an upwardly opening pocket to receive a card and being adapted to be connected at its front and rear to the adjacent members to permit limited sliding movements relatively thereto, and means for increasing the frictional contact between each member and its card consisting of an embossed area in the material of each member opposite one face of its 80 card.

14. In an index system, the combination of a container, a series of expandable card-holding units mounted in said container, each of said units comprising a plurality of individual card-holding members of fibrous material placed one behind the other and normally supported in upright position in said container, each of said members being adapted 90 to have limited sliding movement in a vertical direction relative to the member in front thereof, means for anchoring the foremost member of each unit in said container, a guide card attached to the rearmost member of each unit, a blade of resilient material 100 extending vertically behind said guide card and having frictional sliding engagement therewith, a U-shaped clip at the lower end of said blade and adapted to embrace the lower edges of the card-holding members of each unit, and means for supporting said clip in the container.

15. In an index system, the combination of a container having a central longitudinal slot at its bottom and a rod extending from front to rear in said slot, a plurality of expandable units mounted in said container, each unit comprising a plurality of individual card-holding members connected with each other for limited relative displacement, 110 a card secured to the foremost member and anchored to said rod at its lower edge, a guide card secured to the rearmost member, a blade of resilient material extending vertically behind said guide card and having a 120 hole at its lower end engaged by said rod, and a U-shaped extension beneath said hole and extending forwardly and upwardly in front of said anchored card, and a slide fixed adjacent the lower edge of said guide card 125 and mounted on said blade for frictional sliding movement thereon, and stops at either end of said blade for limiting the vertical movement of said guide card.

16. In a card index system, the combina- 130

tion of an expansible unit comprising a plurality of card-holding members adapted to be engaged with each other for relative displacement, and means for holding said unit in expanded position.

17. In a card index system, the combination of an expansible unit comprising a series of card-holding members adapted to be engaged with each other for relative displacement, in the expansion of said unit, and frictional means acting on said unit to hold the same in expanded position.

18. In a card index system, the combination of an expansible unit comprising a series of card-holding members adapted to be engaged with each other for relative displacement, in the expansion of said unit, and frictional means for holding said unit in expanded position including a stop member for limiting the expansion of said unit.

19. In a card index system, the combination of a container, a plurality of expansible units supported in said container, each unit comprising a series of card-holding members movable in their own planes relative to each other in the expansion of said unit, and means for defining the space occupied by each unit in said container.

20. In a card index system, the combination of a container, a plurality of expansible units adapted to be arranged one behind the other lengthwise of said container, each unit comprising a series of card-holding mem-

bers shiftable in their own planes relative to each other in the expansion of said unit, and a member extending perpendicular to the planes of the members of each unit and longitudinally of said container, said members having their ends in abutting contact.

21. In a card index system, the combination of a container, a plurality of expansible units adapted to be arranged one behind the other lengthwise of said container, each unit comprising a series of card-holding members shiftable in their own planes relative to each other in the expansion of said unit, and U-shaped members embracing the lower portions of said units and having abutting engagement at their ends for determining the longitudinal space occupied by each unit in said container.

22. In a card index system, the combination of a series of individual upright card-holding members of sheet material folded to form pockets and connected together for limited relative vertical displacement, a card inserted in each of said pockets with its edge normally seating at the bottom of said pocket, and means for insuring the retention of said cards in said pockets consisting of projections formed in the material of each pocket, and engaging said cards.

Signed at Muskegon, Mich., this 28th day of March, 1927.

DAVID E. HUNTER.
